UNITED STATES PATENT OFFICE.

DARIUS GALLAGHER, OF NEW YORK, N. Y.

FOUNTAIN-PEN.

971,742.

Specification of Letters Patent. Patented Oct. 4, 1910.

Application filed December 18, 1909. Serial No. 533,75.

To all whom it may concern:

Be it known that I, DARIUS GALLAGHER, a citizen of the United States of America, residing at New York city, in the county of New York and State of New York, have invented certain new and useful Improvements in Fountain-Pens, of which the following is a specification, reference being had therein to the accompanying drawing.

- 10 This invention relates to that class of fountain pens which are composed of three main sections, the pen-point section, the reservoir section and the point protecting section, which when assembled constitute the ordinary stylographic writing pen. Such pens when empty of ink necessitate the unscrewing and removal of the pen-point section to open the reservoir section so that it can be filled by a dropper or otherwise.
- 15 Heretofore it has been proposed to provide the reservoir section with a cap protector having the characteristics of a suction-bulb which when removed from over the pen-point could be applied to the opposite end of the pen to draw the ink up through the point of the holder into the reservoir and thereby fill it by suction after the manner of an ordinary dropper.

25 The object of my device is to overcome many of the objectionable features of such combined fillers and point-protectors by certain peculiar features and combinations to be more fully described hereinafter and pointed out in the claims.

- 30 In the accompanying drawings, Figure 1 represents a side-elevation wherein my improvements are also shown in longitudinal section with the parts arranged in open adjustment and coupled ready for filling, and Fig. 2, the same kind of a view wherein the parts are shown in closed adjustment ready for writing or to be placed and carried in the pocket of the user.

35 The numeral 1 indicates a tubular reservoir and pen-holding section, 2 a substantially cylindrical elongated hollow cap section, and 3 a combined point cover and suction bulb. The reservoir section 1, is provided with a reduced half 4 having external 40 threads 5 commencing at a shoulder 6 and extending toward the end of the section for about half an inch or more in order to make a tight joint when the cap section is applied. The end of section 1 is closed by an integral 45 end-wall 7 with the exception of a small vent 8 located slightly to one side of the longi-

tudinal axis of the section. The cap section 2 is internally threaded to screw on to the external threads 5 of the reservoir, and is given an interior diameter which allows 50 it to loosely telescope over the reduced half 4 of the reservoir. The external diameter of the cap section 2 is the same as that of the main portion of the reservoir whereby, when the two sections are coupled together, 55 their outer surfaces will be smooth and flush with each other to provide the usual symmetrical pen holder.

The means for filling the pen consists of the detachable suction bulb 3 which fits 70 over the end of cap section 2, and when compressed, forces the air out of the bulb through a hole 10 in the head of the cap, and thence through the vent 8 out through the reservoir when the parts are in open adjustment 75 as seen in Fig. 1. When pressure is removed from the bulb a contrary action will ensue and suck the ink up into the reservoir, it being understood that the end of the reservoir 1 is first immersed in ink. In this 80 operation the action is precisely like that of an ordinary glass tube and bulb dropper. This mode, however, of filling a fountain pen is old and well known to the art. To utilize the idea for every-day practical use, 85 and to provide a small, symmetrical pen which can be readily understood and operated by the average person, I make the end wall 7 of the reservoir act as a valve, which seats against a rubber washer 14 fitting 90 snugly within the inner end of the cap section 2, whenever the latter is screwed up against the shoulder 6 as seen in Fig. 2. When the parts are thus closed, pressure upon the bulb will have no effect upon the 95 ink in the reservoir and it cannot be expelled by accidentally compressing the bulb while in the pocket of the user. A plug 11 on the end of the reservoir enters the hole 10 in the cap and closes it against leakage or the entrance of dust and dirt which might otherwise work into the ink while the pen is in one's pocket.

My combined pen cover and suction bulb 3 is substantially cylindrical and is by preference made of resilient rubber glazed upon the outside with a suitable enamel and adapted to fit over the cap section 2. To make a tighter joint, and to prevent the rubber from becoming too slack where it 105 fits over said end, I provided a split ferrule 13 composed of steel or other strong spring

metal. This ferrule embraces the end of the rubber bulb and is fixed thereto in any suitable manner.

15 is a clip secured to the ferrule and extending along the side of the bulb by means of which the pen may be fastened to a vest pocket. This clip acts as a backing for the thumb or finger in compressing the bulb as shown in dotted lines in Fig. 2.

16 My combined suction bulb and pen cover 3 is adapted to be removed from over the pen and carried on the opposite end while writing in the customary manner.

What I claim is:

15 1. In a fountain pen the combination with the body-portion of the pen, of a combined pen cover and pocket clip consisting of a rubber bulb having an open end adapted to fit over and be closed by either end of said 20 body-portion, an expansible and contractible ferrule attached to and embracing the open end-portion of said bulb, whereby the material of the bulb serves as an elastic washer for said ferrule, and a hook-portion 25 secured to the ferrule and extending alongside the bulb to serve as a backing for the operator in the act of compressing the bulb.

2. In combination with the body-portion of a fountain pen, a combined pen-cover and

30 pocket clip consisting of a rubber bulb having a clip device attached thereto and extending alongside the bulb to form a backing in the act of compressing the bulb.

3. In a fountain pen the combination with the body-portion of the pen, of a rubber 35 suction bulb having an open end adapted to fit over one end of said body-portion, and a pocket clip device attached to the bulb whereby the body-portion of the pen is retained in one's pocket through the medium of the bulb which is in turn held by the clip-device, said clip device extending alongside the bulb to form a backing in the act of compressing the bulb.

4. In a fountain pen, the combination with 40 the body-portion of the pen, of a suction bulb having an open end adapted to fit over one end of said body-portion, and a clip-device secured to the bulb, said clip device extending alongside the bulb to form 45 a backing for the operator in the act of compressing the bulb.

In testimony whereof I affix my signature in presence of two witnesses,

DARIUS GALLAGHER.
